SUPPORT AND OPENER FOR FLUID DISPENSING CONTAINERS

Filed June 3, 1939

UNITED STATES PATENT OFFICE

2,210,789

SUPPORT AND OPENER FOR FLUID DISPENSING CONTAINERS

George B. Applegate, Pennsville, N. J.

Application June 3, 1939; Serial No. 277,285

3 Claims. (Cl. 221—23)

My invention relates broadly to dispensing containers and more particularly to the construction of a support and opener for sealed metallic containers for fluid in combination with means for 5 adjustably directing the fluid from the container.

One of the objects of my invention is to provide a construction of manually controllable device for supporting and aperturing a sealed container and delivering fluid therefrom.

Another object of my invention is to provide 10 a construction of manually controllable device having means for detachably securing a sealed metallic container in position, aperturing the container and confining the fluid contents from the 15 container into a stream in any desired direction.

Still another object of my invention is to provide 20 a manually controllable device having an angularly shiftable spout connected therewith adapted to be moved beneath a sealed liquid container which may be both supported and apertured by the manually controllable device for 25 delivering the fluid contents in a confined stream in a desired direction.

Other and further objects of my invention 30 relate to a simplified and inexpensive construction of support and opener for fluid dispensing containers as set forth more fully in the specification hereinafter following by reference to the accompanying drawing, in which:

30 Figure 1 is a side elevational view of the support and opener for fluid dispensing containers constructed in accordance with my invention and illustrating the means for confining the stream which is angularly shiftable over a relatively wide 35 range of positions; Fig. 2 is a front elevational view of the device of my invention illustrated on a somewhat larger scale; Fig. 3 is a top plan view of the device, the stream confining means being broken away at one side; Fig. 4 is a longitudinal sectional view taken through the device 40 of my invention; Fig. 5 is a fragmentary sectional view showing the device of my invention in the position which it occupies when the sealed metallic container is apertured to release the fluid 45 contents for delivery to the funnel which confines the stream of fluid in the desired direction; Fig. 6 is a fragmentary transverse sectional view taken on line 6—6 of Fig. 4; Fig. 7 is a fragmentary vertical sectional view on line 7—7 of Fig. 4; Fig. 8 is a pictorial view showing the device of 50 my invention in operation for filling the crank-case of an engine; and Fig. 9 is a transverse sectional view through the cutting element taken on line 9—9 of Fig. 4.

55 My invention is directed to a simplified con-

struction of an angularly controllable device adapted to support a sealed metallic receptacle with means for aperturing the receptacle and directing the fluid contents thereof in a confined stream. The device of my invention is particularly useful in filling stations for dispensing oil from sealed containers for filling the crank-cases of automobiles. The attendant grasps the device in one hand, mounts the sealed can in the support carried by the device, and actuates a cutter for aperturing the can enabling oil to be delivered from the can into an angularly adjustable funnel device. The funnel device is shifted to any desired angle for directing the oil in a confined stream to the crank-case of the automobile. The 15 device is manually operative wholly by one hand by which the sealed container may be supported and apertured for effecting delivery of the fluid contents in a desired direction.

Referring to the drawing in detail, reference 20 character 1 designates a frame member having substantially channel-shaped contour indicated generally at 2 and adapted to be grasped by the hand of the operator. A sliding handle portion indicated at 3 is disposed within the handle 25 portion 2 and is normally urged to a position in spaced relation from the handle portion 2 by means of a spring 4 secured by the post 5 on the fixed handle portion 1 and a connection 3a on the 30 slidable handle portion 3. A stop 1a on the frame member 1 serves as a limit for the movement of slidable handle portion 3 away from the handle portion 1. That is to say, the slidable portion 3 is housed within the channel-shaped section 2 and is projected therefrom by means 35 of spring 4 for a distance limited by stop 1a. The operator by extending the fingers around handle portions 2 and 3 is able to reciprocate handle portion 3 against the action of spring 4 by closing the fingers of the hand under the slidable 40 handle portion 3, whereby slidable handle portion 3 may be telescopically moved into the recess provided by channel-shaped handle portion 2.

Fig. 5 illustrates the compressed position of the 45 slidable portion 3 with respect to the fixed handle portion 2 from which it will be observed that slidable portion 3 carries a cutting member which serves as a means for aperturing a sealed metallic container for discharging the fluid contents therefrom. The cutting member is constituted 50 by a cutting point 11 and cutting blades 12 co-extensive therewith. The cutting point 11 and cutting blades 12 are formed on channel member 9 which is supported by means of bolt members 10 which pass through the lowermost end of slid- 55

able portion 3 and through spacers 6 and spacing block 8 and through the channel member 9 where the bolt members 10 are engaged by nuts 10a. The spacers 6 extend through the slot 6a in the lower end of the frame member 1 and serve as a guide means for the lower end of slideable portion 3 with respect to the frame member 1. The spacers 6 so operate the spacing block 8 from the frame member 1 that slideable portion 3 is clear to reciprocate up and down carrying the cutting member therewith. In order to support the sealed metallic container 14 in a position in which the container may be apertured and the fluid contents delivered therefrom, I provide 15 curved arms 15 coextensive with opposite sides of stationary frame member 1. Up-turned lugs 16 are provided on arms 15 for gripping the lower angular edge of the sealed container 14. The stationary frame member 1 carries a similar pair 20 of arms 17 adjacent the upper end of frame member 1 spaced from the arms 15 a distance substantially equal to the depth of the sealed container. The arms 17 have lugs 18 extending substantially at an obtuse angle with respect 25 thereto to allow the sealed container to be readily moved into position between the sets of lugs 18 and the sets of lugs 16. For purposes of latching the sealed container in position, I provide a spring actuated latch 19 which is pivoted at 20 between 30 a pair of outwardly projecting arms 21. A spring member 22 engages the latch 19 tending to normally maintain the latch in the position illustrated in Figs. 4 and 5.

The latch 19 has a cam-shaped lower edge 23 35 against which the upper peripheral edge of the sealed container 14 slidably engages as the sealed container is moved into position on the carrier allowing latch 19 to be thrust upwardly until the end thereof indicated at 24 engages beneath the beaded upper peripheral edge of the sealed container at which time the spring 22 engaged in notch 25 of latch 19 moves the lower end 24 of the latch into position, securing the beaded peripheral edge of the can against displacement. 40 When the empty can is to be removed, the end of the latch 19 is depressed by the finger of the operator, retracting the engaging end 24 of the latch and allowing the sealed container to be readily removed from the support.

50 The stationary frame member 1 has a limiting stop 1a extending therethrough as previously described, forming an abutment serving to limit the maximum projection of the slideable portion 3. The member constituting the limiting stop 1a 55 also serves as a pivot means for yoke member 26 and bracing members 27 which are secured at their lower ends to the funnel shaped member 28. The yoke member 26 directly connects with the upper peripheral edge of the funnel-shaped member 28 as shown at 26a while the extremities of the bracing members 27 connect at 29 with the interior portion of the funnel-shaped member 28. The delivery spout 30 of funnel-shaped member 28 may be directed into the orifice at 60 which the oil is to be delivered as represented generally in Fig. 8.

I have shown the device of my invention in the process of filling the crank-case of an engine in the schematic view shown in Fig. 8 where spout 70 30 projects into the pipe leading to the crank-case at 31 with the handle control portion and sealed container displaced at an angle thereby allowing the filling device to be used where space is congested adjacent the engine hood. The filling device may be first placed in position, select-

ing the proper angularity between funnel-shaped member 28 and the hand supporting device. Slidable portion 3 may then be drawn toward frame member 1 aperturing the sealed container by the rupturing of the can by movement of the cutting point 11 and cutting blades 12 through the lower end of the can as shown in Fig. 5. The fluid contents pour from the can and are directly guided into the funnel-shaped member 28 and through the spout 30 to the place of consumption. Because of the adjustability of the funnel-shaped member in angularity, the stream of fluid from the sealed container may be confined in a predetermined path with minimum loss of the fluid and directed in any desired direction. 15

The channel member 9 that is provided with cutting point 11 and cutting blades 12 is readily replaceable when it has become dull by removal of nuts 10a, removal of the dull member 9, and replacement by a sharp cutter which is secured 20 in position by screwing and tightening up nuts 10a.

The device of my invention may be quickly loaded with a sealed container and the empty can readily removed and a renewal container 25 readily positioned on the support. The aperturing operation is quickly performed with minimum effort and by one hand of the attendant. In confined spaces generally found about an automobile engine, the device of my invention 30 has been found highly convenient in operation because of the wide angular sweep through which the support may be moved with respect to the funnel-shaped member while at the same time 35 insuring the delivery of the fluid contents to the interior of the funnel shaped member.

I have found the embodiment of my invention herein shown and described highly practical in manufacture, production and use. However, while I have described my invention in one of its 40 preferred embodiments, I desire that it be understood that modifications may be made and that no limitations upon my invention are intended other than may be imposed by the scope of the appended claims. 45

What I claim as new and desire to secure by Letters Patent of the United States is as follows:

1. A dispensing device comprising in combination a frame member, a yoke pivotally mounted adjacent one end of said frame member, a funnel device connected adjacent the periphery thereof with said yoke, brace members extending from the pivot point of said yoke to spaced points of support on said funnel device whereby said funnel device may be moved to various angular positions 50 with respect to said frame member, means carried by said frame member for detachably receiving and supporting a sealed container for fluid, a cutter mounted adjacent said frame member and located substantially intermediate 55 the sealed container for fluid and said funnel device, and means associated with said frame member for moving said cutter for rupturing said sealed container for fluid whereby the fluid contents thereof may be discharged into said 60 funnel device when said funnel device is shifted to a desired angular position with respect to said frame member. 65

2. A dispensing device comprising in combination a frame member, a yoke pivotally mounted 70 adjacent one end of said frame member, a funnel device connected adjacent the periphery thereof with said yoke, brace members extending from the pivot point of said yoke to spaced points of support on said funnel device whereby said 75

funnel device may be moved to various angular positions with respect to said frame member, means carried by said frame member for detachably receiving and supporting a sealed container for fluid, a cutter mounted adjacent said frame member and located substantially intermediate the sealed container for fluid and said funnel device, and a reciprocative member slideable with respect to said frame member, spring means for normally maintaining said reciprocative member in spaced relation to a portion of said frame member, means for supporting said cutter on said reciprocative member whereby said reciprocative member may be manually moved with respect to a portion of said frame member for shifting said cutter and rupturing said sealed container for fluid for discharging fluid contents therefrom into said funnel member with said funnel shaped member in a selected angular position with respect to said frame member.

3. A dispensing device comprising a frame

member of substantially channel shaped contour terminating in a hand grip portion, a slidable member telescopically disposed within the channel shaped frame member and terminating in a complementary hand grip portion adjacent said first mentioned hand grip portion, means for detachably receiving and mounting a sealed container for fluid on said frame member, a funnel shaped device pivotally mounted adjacent the end of said frame member substantially beneath said sealed fluid container, and a detachable cutter device mounted on said shiftable member in a position intermediate said funnel shaped device and said container and operative for rupturing said container when said hand grip portions are moved toward each other for discharging fluid into said funnel shaped device in any one of its selected angular positions with respect to said frame member.
